UNITED STATES PATENT OFFICE

158,263

DRY POWDER FIRE EXTINGUISHER OR SIMILAR ARTICLE

Leo Gordon, Nutley, N. J., assignor to Specialties
Development Corporation, Belleville, N. J., a
corporation of New Jersey

Application May 18, 1949, Serial No. 2,733

Term of patent 14 years

(Cl. D16—2)

To all whom it may concern:

Be it known that I, Leo Gordon, a citizen of the United States, residing in Nutley, in the county of Essex, in the State of New Jersey, have invented a new, original, and ornamental Design for a Dry Powder Fire Extinguisher or Similar Article, of which the following is a specification, reference being had to the accompanying drawing, forming a part thereof.

Figure 1 is a front elevational view;

Figure 2 is a rear elevational view; and

Figure 3 is a top plan view of a dry powder fire extinguisher or similar article showing my new design.

I claim:

The ornamental design for a dry powder fire extinguisher or similar article, substantially as shown.

LEO GORDON.
